Application September 11, 1950, Serial No. 12,138
In Canada August 22, 1950

Term of patent 14 years

(Cl. D34—15)

To all whom it may concern:

Be it known that I, Donald H. Stevens, a citizen of the Dominion of Canada, residing at Oakville, in the county of Halton and Province of Ontario, Dominion of Canada, have invented a new, original, and ornamental Design for a Toy Bow Gun or Similar Article, of which the following is a specification, reference being had to the accompanying drawing, forming a part thereof.

Fig. 1 is a top plan view of a toy bow gun or similar article, showing my new design;

Fig. 2 is a side elevational view thereof; and
Fig. 3 is a front elevational view thereof.

The dominant features of my new design are shown in solid lines in the drawing. The dotted line showing of a representative dart is for illustrative purposes only.

I claim:

The ornamental design for a toy bow gun or similar article, as shown and described.

DONALD H. STEVENS.
